RIBBON-LIKE WRAPPING MATERIAL

Ferdinand K. Goetz, Reading, Pa., assignor to Schoenerer Candies, Inc., Reading, Pa., a corporation of Pennsylvania

Filed Sept. 12, 1962, Ser. No. 71,660

Term of patent 14 years

(Cl. D59—2)

The figure is a plan view of a ribbon-like wrapping material embodying my new design.

The characteristic feature of my new design resides in the specific, sinuous broken stripe of contrasting color extending lengthwise of the ribbon-like wrapping material, substantially as shown.

I claim:

The ornamental design for a ribbon-like wrapping material, substantially as shown and described.
